Application June 18, 1937, Serial No. 148,894

18 Claims. (Cl. 250—20)

This invention relates to modulated-carrier signal receivers and, more particularly, to methods of, and means for, controlling the selectivity and fidelity of reproduction of such receivers to 5 reduce the effects of undesired signal disturbances.

In the present system of broadcasting, different signals are transmitted on carrier frequencies usually separated by multiples of 10 kilocycles, while the modulation sidebands of each signal cover ranges of frequency extending as much as 8 kilocycles above and below their respective carrier frequencies. In order to obtain the highest possible fidelity of reproduction 15 of the desired signal consistent with the conditions of reception, it is necessary that various characteristics of the receiver be so controlled as to reduce the effects of undesired signal disturbances. These disturbances may be of various types which, for convenience, may be divided 20 into two classes: (1) those which are substantially continuous, including steady noise having its power distributed over the audio-frequency range and beat-note interference resulting from 25 modulation of the desired signal carrier by carriers of undesired signals adjacent the desired signal carrier; and (2) disturbances of an intermittent or discontinuous type, including electrical transients or sharp impulses and distortion 30 of the desired signal due to detuning during the tuning operation.

Heretofore, various systems have been devised for automatically controlling the selectivity and fidelity of reproduction of radio receivers in accordance with received signal conditions. In all 35 of such systems in which the control has been effected in accordance with undesired signal disturbances, it has been dependent, at least in part, upon the amplitude of such disturbances and 40 these disturbances could be differentiated from the desired signal only when their amplitude was of the same order of magnitude as the desired signal amplitude. It is desirable, however, to provide a control of the receiver characteristics 45 such as will reduce the effects of undesired signal disturbances even when they are materially weaker than the desired signal.

It is an object of the present invention, therefore, to provide an improved method of, and 50 means for, controlling the characteristics of a modulated-carrier signal receiver to reduce the effects of undesired signal disturbances, regardless of their amplitude relative to that of the desired signal.

55 Briefly stated, this object is achieved by pro-

viding a modulated-carrier receiver comprising means for selecting a carrier having a first characteristic type of modulation representing a desired signal, but subject to modulation of said first type as well as modulation of a second characteristic type by undesired signal disturbances, together with means for selectively detecting and utilizing only the modulation of the first type to 5 reproduce the desired signal. Means are further provided for selectively detecting and utilizing 10 only the modulation of the second type to so control the characteristics of the receiver as to reduce the effects of the undesired signal disturbances.

Thus, the present invention is based upon the 15 principle that signal disturbances, in general, cause several types of modulation of the desired signal carrier, for example, both amplitude and frequency modulation. While it is theoretically possible for a disturbance to produce only one 20 kind of modulation at a given instant, these different types of modulation are ordinarily produced at the same time and their probable coincidence makes it possible to obtain adequate control by operating control circuits in response to 25 modulation of the type which is not being utilized to reproduce the desired signal. In this specification and in the appended claims, the term "type of modulation" is utilized to designate 30 the manner in which a carrier wave is varied 35 by a desired signal or by undesired signal disturbances. For example, variations of one characteristic of a carrier wave, such as its amplitude, constitute modulation of the amplitude type, while variations of a different characteristic of a carrier wave, such as its frequency, constitute 40 modulation of the frequency type. That is, the term does not refer to the type of signal effecting the modulation but to the particular manner in which any desired or undesired signal modulates a carrier wave, that is, to the characteristics 45 which are modulated.

In accordance with one feature of the invention, the control means are designed to be responsive only to modulation of the desired signal 45 of the second type by substantially continuous disturbances. The receiver includes a band-pass selector for selecting the desired signal and the control means serves to adjust the width of the band of frequencies passed by the selector in 50 accordance with the amplitude of the undesired signal disturbances, thereby to reduce the effects thereof. The adjustment of band width is preferably obtained in the carrier-frequency channel 55 of the receiver, but the equivalent effect may also

be obtained by proper adjustment of the width of the audio-frequency band passed by the system. The continuous disturbances may, for example, be steady noise, which is understood to 5 include rapidly recurring clicks, or they may comprise beat-note signals such as are developed by modulation of the desired signal carrier by the carrier of a signal adjacent the desired signal and, in this case, the control means may include 10 means selectively responsive only to these beat-note signals for effecting the band width adjustment.

In accordance with another feature of the invention, the control means is designed to be 15 responsive to undesired signal disturbances of an intermittent or discontinuous type and operates to suppress the reproduction of such undesired signals, as well as the desired signals, for the duration of the disturbance. These discontinuous 20 disturbances may, for example, be electrical transients of very short duration, so that the suppression of the reproduction does not appreciably disturb the program, or they may constitute undesired distortions of the desired signal such as are developed in the receiver when 25 detuned during the tuning operation.

For a better understanding of the invention, together with other and further objects thereof, reference is had to the following description 30 taken in connection with the accompanying drawings, and its scope will be pointed out in the appended claims.

In the accompanying drawings, Fig. 1 is a schematic diagram of a radio receiver embodying 35 one form of the present invention; Fig. 2 is a similar diagram illustrating another form of the invention; Fig. 3 is a schematic diagram of a complete superheterodyne receiver based on the fundamental arrangement illustrated in Fig. 1 and including control circuits embodying various 40 features of the present invention; and Fig. 4 is a circuit diagram showing representative circuits which may be used in the portions of the receiver of Fig. 3 embodying the present invention.

Referring now more particularly to Fig. 1, there is shown schematically a receiver embodying a carrier-frequency amplifier and selector 10 having its input circuit connected with an antenna 11 and ground 12. A main signal-detecting, amplifying, and reproducing channel is connected to the output circuit of the amplifier and selector 10 and includes, in the order named, an amplitude-modulation detector 13, a modulation amplifier 14, and loud-speaker 15, in accordance with conventional practice.

The portion of the receiver described being conventional, a detailed description thereof is unnecessary. Briefly, however, a carrier amplitude modulated by a desired signal is intercepted by the antenna, selected and amplified in the amplifier 10, and delivered to the amplitude-modulation detector 13, wherein the audio-frequency signal is derived. The latter signal is further amplified in the amplifier 14 and supplied in the usual manner to the loud-speaker 15 for reproduction.

In accordance with the present invention, a control channel is connected to the output circuit of the amplifier and selector 10 and includes, in the order named, a frequency detector 16 and rectifier 17. Certain of the circuits of the main channel of the receiver are arranged to be so controlled as to reduce the effects of 75 undesired signal disturbances, as, for example,

by adjusting the width of the band of desired signal frequencies passed by the system or by entirely suppressing the reproduction of both the desired and undesired signals for the duration of the latter. While such arrangements are explained in detail in connection with the description which follows with respect to Figs. 3 and 4, in the present instance, for the purpose of brevity, such circuits, per se, are not shown, but suitable circuits of this type will be considered 10 as included in the amplifier and selector 10 and the amplifier 14, adapted for adjustment by means of control-bias voltages. The output of the rectifier 17 is connected by suitable leads 18 and 19 to the amplifier and selector 10 and 15 to the amplifier 14, respectively, to supply these control-bias voltages.

In the operation of the system shown in Fig. 1, the desired amplitude-modulated signal is detected by the amplitude-modulation detector 13 20 and amplified and reproduced in the manner described above. Undesired signal disturbances generally effect both amplitude and frequency modulation of the desired signal, however, and the modulation of the latter type only is selectively detected by the frequency-modulation detector 16 and rectified by the rectifier 17 to develop control-bias voltages variable in accordance with these disturbances. These voltages are applied to the amplifier and selector 10 and 30 to the amplifier 14 so to control the characteristics of the receiver as to reduce the undesired signal disturbances.

In Fig. 2 there is illustrated a modified form 35 of the invention designed for the reception of carrier signals frequency-modulated by the desired signal. The receiver of Fig. 2 is similar to that of Fig. 1, except that here the main channel includes a frequency-modulation detector 13a, instead of the amplitude-modulation detector 13 40 of Fig. 1, and the control channel includes an amplitude-modulation detector 16a, instead of the frequency-modulation detector 16. Other corresponding parts of the two receivers are indicated by the same reference numerals. The 45 only difference in the operation of the receiver of Fig. 2 with respect to that of Fig. 1 is that in the arrangement of Fig. 2 the desired signal is solely frequency-detected in the main channel and the undesired signal disturbances are solely 50 and selectively amplitude-detected in the control channel to develop the control-bias voltages.

Referring now to Fig. 3, there is shown a complete superheterodyne radio receiver embodying 55 the present invention for effecting various different types of control in accordance with various kinds of undesired signal disturbances. In general, the receiver of Fig. 3 includes a tunable radio-frequency amplifier and frequency changer 20, having its input circuit connected to an antenna 21 and ground 22. Connected to the output circuit of the amplifier and frequency changer 20, in the order named, and constituting the main channel of the receiver are an adjustable band-pass intermediate-frequency amplifier 23, an intermediate-frequency limiter 24, a moderately sharp intermediate-frequency selector 25, an amplitude detector 26, a sharp cutoff audio-frequency amplifier 27, a manual audio-frequency attenuator 28, an adjustable 60 band-pass audio-frequency amplifier 29, a sharp cutoff push-pull audio-frequency amplifier 30, and a loud-speaker 31. The receiver also includes an automatic amplification control circuit coupled to the output circuit of the amplifier and 75

frequency changer 20 and comprising a broad-band intermediate-frequency amplifier 34 and an A. V. C. rectifier 35, the latter being connected by a suitable lead 36 to the grids of one or more of the tubes in the amplifier and frequency changer 20.

Neglecting for the moment the remaining control circuits of the receiver, as well as the particular features of the circuits of the main channel which are in accordance with the present invention, the system as thus far described includes the features of a conventional superheterodyne receiver. Since the operation of such a receiver is well understood in the art, a detailed explanation thereof is unnecessary. Briefly, however, signals intercepted by the antenna 21 are selected and amplified and converted into intermediate-frequency signals in a conventional manner in the amplifier and frequency changer 20. The intermediate-frequency signals are thereupon selected and translated by the amplifier 23, limiter 24, and selector 25, to the amplitude-detector 26, wherein the audio-frequency signal is derived. The latter signal is further amplified and translated, by way of amplifier 27, attenuator 28, which may be adjusted to give the desired volume output, and amplifiers 29 and 30, to the loud-speaker 31 for reproduction.

Any suitable adjustable selector system, per se, may be employed in the amplifier 23. As will be described hereinafter with reference to Fig. 4, however, in the preferred embodiment of the invention, this amplifier comprises an arrangement whereby the amplification therein, as well as the shape and width of its band-pass characteristic curve, may be adjusted by varying biasing potentials applied to control electrodes of its tubes as a function of the amplitude of the received desired signal as well as the amplitudes of undesired signal disturbances. More particularly, this amplifier comprises circuits so arranged that the width of the band of frequencies passed thereby is controlled directly, and the gain is controlled inversely, in accordance with variations of a positive biasing potential applied to a control terminal thereof, while the band width is controlled directly in accordance with a negative-biasing potential applied to another control terminal thereof. In order then to produce the required positive-biasing potential for automatically controlling the amplification in, and adjusting the width of the band of frequencies passed by, the amplifier 23, there is provided a broad-band intermediate-frequency amplifier 32 with its input circuit coupled to the output circuit of the limiter 24 and a rectifier 33 coupled to the output circuit of the amplifier 32. This amplifier and rectifier may be of conventional design to develop a unidirectional voltage which is variable in accordance with the intensity of the desired and undesired signal voltages supplied thereto. The unidirectional voltage from the rectifier 33 is applied positively by a suitable lead 33a to reduce an initial negative-bias potential on the first above-mentioned control terminal of the amplifier 23, thereby to reduce the gain of, and increase the width of the band of frequencies passed by, this amplifier directly in accordance with this unidirectional voltage. The control-bias voltage developed by the rectifier 33 being proportional to the amplitude of the total signal input thereto, a substantially uniform desired signal output is obtained from the amplifier 23.

In order to control the signal input amplitude

to the rectifier 33 in accordance with the intensity of the received signals and thereby indirectly to control the gain and band-pass characteristic of the amplifier 23, this relation being essential to obtain the full benefit of expansion, intermediate-frequency amplifier 34 is designed to pass a broad band of frequencies including not only the desired signal, but also all undesired signals which are passed by the radio-frequency amplifier and frequency changer 20 and which have sufficient amplitude to be capable of overloading the frequency changer or causing interference and, preferably, it is most responsive to undesired signals on adjacent channels. The rectifier 35 is designed in a conventional manner and operates to develop a unidirectional bias voltage proportional to the amplitude of the total signal voltage proportional to the amplitude of the total signal voltage supplied thereto. Since, as explained above, this bias voltage is effective to adjust the amplification in unit 20 inversely in accordance with the signal input to the rectifier 35, in the presence of interfering signals the amplitude of the signal input to the amplifier 23 and to the amplifier 32 is reduced, with resultant contraction of the band width of amplifier 23.

The intermediate-frequency limiter 24 comprises a circuit so designed as to cut off peaks of noise impulses, the amplitudes of which exceed the peak value of the desired signal. The peak value of the desired signal is twice the peak value of its carrier and the limiter is, therefore, designed to operate at that level. The limiter thus serves to prevent noise peaks from interfering with the operation of the control circuits which are coupled to its output circuit.

The moderately sharp intermediate-frequency selector 25 may be of conventional design and serves to provide more selectivity in the main channel than that of the control channel comprising amplifier 32. Further, with such an arrangement, the amplitude of the signal applied to the detector 26 is substantially reduced by the selector 25 when the receiver is slightly off tune which is, of course, desirable. The attenuator 28 is a conventional manual volume level control, such as is employed in ordinary receivers having automatic amplification control.

Referring now to the control circuits of the present invention, for the purpose of detecting undesired discontinuous or transient signal disturbances appearing as frequency modulation on the desired signal, as, for example, when the receiver is being tuned, there is connected to the output circuit of the intermediate-frequency amplifier 32, in the order named, an intermediate-frequency limiter 37, a broad-band intermediate-frequency amplifier 38, a frequency-modulation detector 39, and a full-wave rectifier 40. The output circuit of the rectifier 40 is connected by a lead 40a to a control-bias terminal of the sharp cutoff audio-frequency amplifier 27. The limiter 37 is adjusted to operate at a level so low as to compress the carrier and modulation down to a constant amplitude which is substantially less than the amplitude which the carrier would have if the limiter were omitted. This provides not only a uniform carrier amplitude for the frequency-modulation detector 39, but also substantially removes the amplitude modulation, which is undesired in frequency-modulation detection. The limiter, while thus being desirable, is not, however, essential.

In the operation of this part of the system, the output of the limiter 37 is amplified by the am-

plifier 38 and the undesired disturbances appearing as frequency modulation on the desired signal are detected by the detector 39. The detected potential from the detector 39 is rectified by the rectifier 40 in such manner as to produce a negative-biasing potential whenever the desired signal carrier is frequency-modulated to a predetermined degree as when the receiver is detuned by a substantial amount on either side of resonance, 10 and this biasing potential is so applied to the amplifier 21 as to quiet the receiver or suppress the reproduction of the desired signal as well as undesired signal disturbances.

The output circuit of the frequency-modulation detector 39 is also coupled to two additional arrangements for controlling other characteristics of the receiver in response to other undesired signal disturbances. One arrangement comprises, connected in the order named, an audio-frequency impulse selector 41, an audio-frequency amplifier 42, and a full-wave rectifier 43 having a negligible time constant. The selector 41 is designed to be somewhat more responsive to higher audio frequencies than to lower frequencies, since noise, such as rapidly recurring impulses or steady background noise, ordinarily has most of its power in the higher audio-frequency range. The selector 41, therefore, is preferably of the high-pass type and, further, has 30 a so-called "negative delay". The last-mentioned characteristic accelerates its response to sharp impulses and thereby renders the control for such impulses more effective.

After selection in the selector 41, the undesired signal disturbances are further amplified in the amplifier 42 and instantaneously rectified with negligible time lag by the rectifier 43, thereby to develop transient negative-biasing potentials which closely follow the undesired signal disturbances. This negative transient potential is applied directly, by way of a suitable lead 44, to the audio-frequency amplifier 30 instantaneously to quiet the receiver during a sharp impulse. The negative-biasing potentials developed by the rectifier 43 are also applied to the negative control terminal of the intermediate-frequency amplifier 23 and to two biasing terminals of the audio-frequency amplifier 29 by way of leads 45, 46, and 47, which include resistors 45a, 46a, 50 and 47a, respectively, for smoothing out these potentials and provide steady biasing potentials, as distinguished from the transient potential applied over the lead 44. The left-hand biasing terminal of the amplifier 29 represents a connection whereby the gain and the band width may be decreased by the application of a negative-bias voltage. The right-hand terminal represents a connection whereby the band width may be decreased and the gain increased by the application of a negative-bias voltage. The biasing potentials applied to these terminals are developed by control circuits of the present invention, as hereinafter further described, and are proportioned to cause negligible resultant change 65 in gain while adjusting the band width. Therefore, the steady potentials derived from rectifier 43 serve to reduce the width of the band of frequencies passed by the amplifiers 23 and 29 when the average noise is sufficiently great to make 70 such control desirable.

The final control arrangement, which is also coupled to the output circuit of the frequency detector 39, includes, in the order named, a beat-note selector 48, a beat-note amplifier 49, 75 and a beat-note rectifier 50. The selector 48 is

designed to be most responsive at frequencies of approximately 10 kilocycles and higher and thus serves to select beat notes produced by carriers on adjacent channels 10 kilocycles or more at either side of the desired signal carrier. These selected beat notes are thereupon amplified by the amplifier 49 and rectified by the rectifier 50 to develop steady biasing potentials. These potentials are applied, by way of leads 51, 52, and 53, to supplement the biasing potentials applied from the rectifier 43 by way of the leads 45, 46, and 47, respectively, and to ensure sufficient contraction of the frequency bands passed by the amplifiers 23 and 29 substantially to avoid the effects of beat-note interference. Diodes 51a, 52a, and 53a are preferably included in the leads 51, 52, and 53, respectively, so that the connections will not by-pass the biasing voltages from the rectifier 43 when the latter are the greater. While the diodes may be replaced by isolating resistors, the use of the diodes renders it possible to disconnect the arrangement including the beat-note selector amplifier and rectifier without affecting the normal operation of the remainder of the receiver.

In Fig. 4 there are illustrated in detail representative circuits embodying the present invention which may be employed in the receiver exemplified in Fig. 3, similar reference numerals being applied to corresponding stages in the two figures. It will, of course, be understood that these detailed circuits are shown simply by way of illustrating one satisfactory embodiment of the invention and that any other suitable equivalent circuits may be substituted therefor, if desired. As illustrated, the amplifier 23 comprises a tuned input circuit 55 loosely inductively coupled to the output circuit 56 of the unit 20 and a tuned output circuit 57 loosely inductively coupled to a tuned input circuit 58 of the intermediate-frequency limiter 24. The input and output circuits 55 and 57 are coupled both forwardly and backwardly by means of directive coupling means, such as vacuum tubes 59 and 60, respectively, input electrodes of the tube 59 being coupled to the circuit 55 and its output electrodes coupled to the circuit 57 and the input electrodes of the tube 60 being coupled to circuit 57 by means of a winding 62, and its output electrodes being inductively coupled back to the input circuit 55 by means of a winding 63. Each of the circuits 55, 57, and 58 is tuned to the intermediate-frequency at which the receiver is operated. Preferably, the circuits 55 and 57 are relatively sharply tuned and have a very low power factor, while the circuit 56 is broadly tuned and has a higher power factor.

By utilizing the tube 59 in the forward coupling means of the amplifier 23 with no phase reversals in its couplings with the circuits 55 and 57, the alternating voltages appearing across the circuit 57 are substantially reversed in phase with respect to the voltages across the input circuit 55 at frequencies in the vicinity of the resonant frequency of the circuits, at which frequencies these circuits are of high impedance and are substantially resistive. A second phase reversal is secured in the backward path in the tube 60 and a third reversal is secured in the coupling between the inductance 63 and the input circuit 58, so that the voltages impressed on the input circuit 55 through this backward coupling path are substantially reversed in phase, at the frequencies indicated, with respect to the input voltage directly impressed on this circuit.

and the system is degenerative to a maximum degree at the intermediate frequency.

At frequencies above the resonant frequency of the circuits 55 and 57, these circuits are capacitive reactive so that the voltages at these frequencies across the circuit 57 lag the input voltages by phase angles approaching 90 degrees. The feed-back voltages at these frequencies impressed on the circuit 55 are similarly retarded by an additional phase angle also approaching 90 degrees, so that the feed-back voltages approach phase coincidence with the input voltages at these frequencies and the coupling system is regenerative therefor. At frequencies below the resonant frequency of the circuits 55 and 57, these circuits are inductively reactive and a similar phase shift occurs, but in opposite sense, so that the system is also regenerative at these frequencies. However, at these limiting frequencies, the impedances of the circuits 55 and 57 are much less than at resonance, the transmission efficiency of the amplifier 23 being reduced and the amplitude of the feed-back voltage also being reduced, so that, while the system is regenerative, it is entirely stable in operation. At frequencies intermediate the limiting frequency just described, the feed-back voltages have intermediate phase angles with respect to the input voltages and the feed-back characteristic of the system has a gradual transition from degeneration to regeneration. Hence, the resultant reduction in amplitude of the frequencies near the intermediate frequency and the increase in amplitude of the frequencies substantially above and below the intermediate frequency impart to the system a band-pass frequency characteristic like that of inductively coupled tuned circuits.

By adjusting the forward and backward coupling reactions between the resonant input and output circuits of the amplifier 23, the amplification obtained between the terminal circuits thereof and the shape of the width of the band-pass characteristic may be controlled as desired. Such coupling control is procured, in accordance with the present invention, by varying the bias potentials applied to the control electrodes of the tubes 59 and 60, a positive biasing potential being applied to the tube 60 from the rectifier 33 and a negative-biasing potential being applied to the tube 59 from the rectifiers 43 and 50, to control the amplification and band-pass characteristic of the amplifier 23, as described above.

The intermediate-frequency limiter 24 comprises the tuned input circuit 58 and a diode limiter tube 64 connected thereacross. A source of biasing voltage, indicated by a battery 64a, is included in the cathode circuit of the diode 64 and provides this tube with a positive cathode bias, the peak value of which is equal to the peak voltage of the signal or twice the peak voltage of the unmodulated carrier itself, so as to by-pass the peaks of noise impulses which exceed this value and prevent their interfering with the operation of succeeding stages of the system. An additional output winding 65 is also included in parallel with the circuit 58, which is designed to provide a very high impedance and preferably is broadly tuned so as not to affect the band width passed by the system.

The stages 25, 26, 27, and 28 are substantially conventional in design and operation. The selector 25 comprises a moderately sharp parallel resonant circuit 66 having its inductance winding 75 coupled to the winding 65 of the limiter 24. The

detector 26 may be a conventional diode rectifier 67 connected as shown across the circuit 66 by way of load resistance elements 68. The amplifier 27 is a conventional sharp cutoff vacuum-tube amplifier 69 having its input circuit connected to the load circuit of the detector 26. The manual attenuator 28 comprises a conventional resistance voltage divider 70 included in the output circuit of the amplifier 69, by adjustment of which the volume level output of the receiver may be controlled in the usual manner.

The adjustable band-pass audio-frequency amplifier 29 comprises an arrangement the construction and operation of which are somewhat similar to that of the amplifier 23, but which is adapted for audio-frequency operation instead of intermediate-frequency operation. The amplifier 29 includes a forward coupling tube 71 and a backward coupling or feed-back tube 72. Attenuation of the frequencies is provided by means of a resistance-reactance network which limits the transmission of very low or very high audio frequencies and in this respect the arrangement is quantitatively quite different from that of the amplifier 23. More particularly, the input circuit of the tube 71 includes a series resistor 71a and series and parallel condensers 73 and 74, respectively. These condensers attenuate the low and high audio frequencies, respectively. The anode circuit tube 71 includes a primary winding 75 of an audio-frequency transformer 76 and a trap circuit, comprising a winding 77 and condenser 78 in series, connected across the winding 75. The trap circuit is tuned to 10 kilocycles, which is the usual frequency difference between carriers on adjacent channels. A part of the voltage developed across the winding 75 is coupled by way of a blocking condenser 79 to the grid of the tube 72. A resistor 81 is included in the cathode circuit of the tube 72 so that an audio-frequency voltage is built up thereacross. This voltage is coupled back by way of a resistor 82 to the grid of the tube 71 to secure feedback which, due to phase shifts effected by the forward and backward couplings, similar to those referred to in connection with the amplifier 23, is degenerative at the mean audio frequencies, but regenerative at lower and moderately higher audio frequencies. The feedback is degenerative also at frequencies higher than the resonant frequency of the trap circuit and this is a desirable condition, since it is desired to attenuate such high frequencies. A grid-leak resistor 83 is connected to the control grid of the tube 71 and this resistor and the resistor 80 are by-passed to ground by way of audio-frequency by-pass condensers 84 for the purpose of smoothing out biasing potentials applied to the control grids of the tubes 71 and 72, as hereinafter explained. These tubes are preferably similar and of the gradual cutoff type. The cathode of each of the tubes 71 and 72 is initially biased positively to prevent the flow of grid current on the signal peaks.

The audio-frequency amplifier 29, under the conditions just described, is adjusted to provide the maximum desired band width by virtue of the feedback through the tube 72. The band width is reduced by the application of negative-biasing potential to the grids of both of the tubes, less potential being applied to the tube 71 than to the tube 72, and these potentials being proportioned to maintain the overall gain substantially constant at frequencies in the middle of the audio-frequency range.

The amplifier 30 comprises a conventional

push-pull arrangement including sharp cutoff vacuum-tube amplifiers 85 and 86 having their control electrodes connected to the secondary winding 87 of the audio-frequency transformer 16. The output circuits of tube 86 are coupled in the usual manner by way of an audio-frequency transformer 88 to the loud-speaker of the system.

The intermediate-frequency amplifier 32 and rectifier 33 are substantially conventional circuit arrangements and preferably include a pentode amplifier 89 having its control grid coupled to the limiter circuit 24 by way of a suitable coupling condenser 90 and leak resistor 91 and including an inductance winding 93 in its anode circuit. The rectifier 33 comprises a diode 94 having an input circuit including a winding 95 coupled to the winding 93 and a load circuit including a resistor 96 and by-pass condenser 97. The amplifier 32 is broadly selective by virtue of its coupling to the limiter 24. A unidirectional voltage is developed by the rectifier 33 across the resistor 96 which is variable in accordance with the intensity of desired and undesired signal voltages in the output of the limiter circuit. A portion of the unidirectional voltage across resistor 96 is applied by way of the resistor 91 as a positive grid bias to the control grid of the amplifier 89 to provide a reverse automatic amplification control, that is, to increase its amplification with increased bias voltage and thereby to secure a substantially level amplification control. In United States Letters Patent No. 2,050,679, granted August 11, 1936 on an application of Harold A. Wheeler, there is described in detail a system embodying a reverse automatic amplification control arrangement similar to that illustrated, and reference may be had to that patent for a detailed disclosure of the principles involved in such a control.

By means of a second connection to the resistor 96 of the rectifier 33 and by way of a suitable lead 33a including a filter resistor 99 and the feed-back winding 62 of the amplifier 23, a positive-bias voltage is also applied to the control grid of the backward coupling tube 60 of the amplifier 23 to increase the degenerative feed-back and thus to reduce the gain and increase the band width of this amplifier with increasing signal input to the rectifier 33, as described above. The net result of this arrangement is that there is obtained a substantially uniform carrier input to the limiter 24 for obtaining satisfactory limiting action and for translation to the subsequent stages of the system.

Referring now to the control arrangement including the stages 31, 38, 39, and 40, the limiter 37 comprises a broadly tuned resonant circuit 100 of high impedance loosely coupled by means of a small condenser 101 to the output circuit of the amplifier 32. Connected across the circuit 100 is a diode 102 having a battery 103 included in its cathode circuit to provide a small positive bias for determining the signal level of the limiting operation. Due to this bias, the voltage across the circuit 100 is limited to a value which is considerably less than the carrier voltage which would otherwise exist across the circuit. The amplifier 38 comprises a pentode amplifier tube 104 having its input circuit connected across the limiter circuit 100, 102. The frequency-modulation detector 39 comprises a frequency-discriminating network 106 and diode rectifiers 107 and 108. The discriminating network includes three inductance windings 109, 110, and 111, of which

the windings 109 and 110 are preferably closely coupled and the winding 111 is moderately or loosely coupled to the winding 109 and incidentally coupled to the winding 110. The windings 109 and 111 are included in resonant circuits 112 and 113, respectively. The circuit 112 includes a shunt resistor 112a to reduce its selectivity. The winding 110 is connected at one end to an intermediate tap on the winding 111 and its opposite end is connected to the cathodes of diodes 107 and 108 by way of load circuits including resistors 114 and intermediate-frequency by-pass condensers 115, as shown, the junctions between the condensers 115 and resistors 114 being by-passed to ground by condenser 116. Each of the two rectifiers thus receives the voltage of the winding 110 and half the voltage of the winding 111, the winding 111 being connected differentially in the two rectifier circuits providing the well-known type of frequency discriminator dependent upon the phase relations of the primary and secondary voltages to obtain asymmetrical frequency characteristics.

A center tapped resistor 117 is connected across the load circuits of the two rectifiers and its center tap is grounded so that equal and opposite rectified voltages relative to ground are obtained from its terminals. While this expedient is ordinarily not employed in frequency detectors, it is utilized here in order to obtain an output voltage which is balanced relative to ground.

The full-wave rectifier 40 comprises two diodes 119 and 120, having their cathodes connected to opposite ends of resistor 117 by way of series resistor 121, by-passed to ground for audio frequencies by condensers 122. A battery 123 is included in the rectifier circuit, as shown, in order to suspend the operation of diodes 119 and 120 until the rectified output exceeds a predetermined small threshold value. The full-wave rectified output of diodes 119 and 120 appears across a resistor 126 in their common load circuit.

When the receiver is properly tuned, the output of the detector 39 comprises only audio-frequency components which do not reach the full-wave rectifier 40. As the receiver is substantially detuned, however, undesired signal disturbances are developed as the result of the dissimilarity of the sidebands passed by the system, as well as the variation in the locally generated oscillation frequencies, and these disturbances appear as both amplitude and frequency modulation on the desired signal carrier. The unidirectional potential in the output of the detector 38, therefore, increases beyond the suspender bias and a unidirectional voltage is developed by the rectifier 40 across the resistor 126. This potential is applied by way of a suitable lead 40a including a series filter resistor 128 to the control grid of the tube 69 of the sharp cut-off audio-frequency amplifier 27, thereby serving to reduce the conductance of this tube to zero and thus quiet the receiver when the receiver is substantially off tune.

In the control arrangement including the stages 41, 42, and 43, the audio-frequency impulse selector 41 comprises the primary winding 129 of a transformer 130 having a center tap connected to ground, shunt resistors 131 connected between its opposite ends and ground, and series condensers 132 connected between its opposite ends and the terminals of the output resistor 117 of the frequency-modulation detector 39. This combination of elements is very broadly resonant at frequencies in the upper part of the audio-fre- 75

quency range. The network is somewhat more responsive to noise than to signal modulation which might accidentally get into these control circuits.

The audio-frequency amplifier 42 comprises a vacuum tube 133 having its input circuit coupled to the secondary winding 134 of transformer 130, and the primary winding 135 of an audio-frequency transformer 136 included in its output circuit. The full-wave rectifier 43 comprises two diodes 138 and 139 connected to the secondary winding 140 of the transformer 136 and having a load circuit comprising resistors 141 and 142. A delay bias is applied to the cathodes of the diodes 138 and 139 from a suitable source, such as a battery 143. Undesired signal disturbances selected by the selector 141 and amplified by the amplifier 42 are rectified in the rectifier 43 with negligible time delay to develop unidirectional voltages across the resistors 141 and 142. The voltage developed across the two resistors is applied by way of the lead 44 directly to the control grids of the amplifier tubes 86 and by way of the leads 45 and 46 including resistors 45a and 46a, respectively, to the control grid of the forward coupling tube 59 of the amplifier 23 and to the control grid of the feed-back coupling tube 72 of the audio-frequency amplifier 29. The potential developed across the resistor 142 is applied by way of the lead 47 including the resistor 47a to the control grid of the forward coupling tube 71 of the amplifier 29. In this manner the biasing voltages developed by the rectifier 43 in response to sharp noise impulses are applied with negligible time delay to the amplifier 30 to reduce its conductance substantially to zero and thereby quiet the receiver for the duration of the impulses, while the biasing voltages developed in response to the average noise received controls the amplifiers 23 and 29 to reduce the width of the frequency bands passed thereby sufficiently to substantially avoid the effect of such noise, as described above.

In the arrangement including the stages 48, 49, 45 and 50, the beat-note selector 48 comprises a transformer 144, the primary winding 145 of which has a center tap connected to ground and is connected across the output resistor 117 of the detector 39 by way of coupling condensers 146. The secondary winding 147 of transformer 144 is connected in series with an uncoupled inductor 148 and a condenser 150 to form a circuit most responsive at frequencies of about 10 kilocycles and higher for selecting beat notes 55 produced by carriers in adjacent channels 10 kilocycles or more at either side of the carrier, as previously explained. More particularly, the beat-note selector 49 has the characteristic of a high-pass filter which is unresponsive at frequencies substantially below 10 kilocycles, has a peak at 10 kilocycles, and is also responsive at higher frequencies, such as 20 or 30 kilocycles.

The amplifier 49 comprises a conventional amplifier tube 151, its input circuit being connected across the beat-note selector circuit and its anode circuit including the primary winding 152 of a transformer 149. The rectifier 50 comprises a conventional diode 154 connected to the secondary winding 155 of transformer 149 and having a load circuit including resistors 156 and 157 shunted by a condenser 158.

Beat notes resulting from the beating of adjacent undesired signal carriers with the desired signal carrier and frequency detected by the detector 39 are selected by the selector 48, amplified

by the amplifier 49, and rectified by the rectifier 50 to develop negative unidirectional biasing potentials across the resistors 156 and 157. The potentials developed across these two resistors is applied by way of the leads 51 and 45 to the control grid of the forward coupling tube 59 and by way of the leads 52 and 46 to the control grid of the backward coupling tube 72 in the amplifier 29. The potential developed across the resistor 156 is applied by way of leads 53 and 47 to the control grid of the tube 71. These biasing potentials serve to supplement the biasing potentials applied from the rectifier 43 to ensure sufficient contraction of the widths of the frequency band passed by the amplifiers 23 and 29 to avoid substantially the effect of the beat-note interference, to which this control arrangement is responsive. The diodes 51a, 52a, and 53a are included in the biasing leads and function as described with reference to Fig. 3.

All of the detectors employed in the system are preferably linear detectors with respect to their essential characteristics. In the amplitude detectors, linear rectification is obtained in the usual manner by loading the diodes with high resistance. The frequency-modulation detector 39 should have, in addition, substantially linear discriminator characteristics over a frequency range of about 20 kilocycles centered on the intermediate frequency. The output of the detector 39 is then proportional to the frequency modulation as long as it does not exceed 10 kilocycles from the mean.

Operating potentials are supplied for the various tubes of the system from suitable sources in conventional manner, batteries having been indicated in the drawings for this purpose.

Since the particular operations of the various control arrangements have already been described in connection with the above detailed description of the apparatus, repetition thereof is unnecessary. To summarize, however, when undesired signal disturbances of the various different kinds are received, they frequency-modulate the desired signal and this signal is amplified by the amplifier 32, limited as to its amplitude by the limiter 37, further amplified in the amplifier 38, and the frequency modulation is detected by the detector 39. When these undesired signal disturbances are such as are caused by improper tuning of the receiver, they are rectified by the rectifier 40 and applied to the amplifier 27 to cut off the conductance thereof and substantially suppress the reproduction of both the undesired signal components and the desired signal during such mistuning. When the signal disturbances are electrical transients or are of the continuous type and distributed throughout the modulation-frequency range, they are translated from the frequency detector 39 to the audio-frequency impulse selector 41, are selected therein and thereupon amplified in the amplifier 42, and rectified in the rectifier 43. Control voltages are thus developed which are proportional to the undesired disturbances of the continuous type and these voltages are applied to the amplifiers 23 and 27 to contract the width of the bands of frequencies passed by these stages of the system in accordance with the amplitude of such undesired signal disturbances, thereby to reduce the effects thereof. Control voltages are also thus developed by the rectifier 43 responsive to the electrical transients of short duration and this voltage is applied directly to the amplifier 30 to cut off this amplifier and thereby suppress

50 55 60 65 70 75

75

the reproduction of both the desired and undesired signals for the duration of such transients.

When the undesired signal disturbances are such as are caused by the presence of an undesired signal on a carrier frequency adjacent the desired signal-carrier frequency, or, in other words, such as result in 10 kilocycle beat notes, these beat notes are detected by the frequency detector 39, selected by the selector 48, amplified by the amplifier 49, and rectified by the rectifier 50. The unidirectional voltages thus developed are applied to supplement the control voltages developed by the rectifier 43 and applied to the amplifiers 23 and 29 and effect the required contraction of the width of the band of frequencies passed by these amplifiers to avoid the effects of such beat-note interference.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A modulated-carrier signal receiver comprising means for selecting a carrier having a first characteristic type of modulation representing a desired signal and subject to modulation of said first type and of a second characteristic type by undesired signal disturbances, means for selectively detecting and utilizing said selected-carrier modulation of the first type to reproduce the desired signal, and means for selectively detecting and utilizing only said selected-carrier modulation of the second type so to control the characteristics of the receiver as to reduce the effects of said undesired signal disturbances.

2. A modulated-carrier signal receiver comprising means for selecting a carrier having amplitude modulation representing a desired signal and subject to both amplitude modulation and frequency modulation by undesired signal disturbances, means for selectively detecting and utilizing said amplitude modulation to reproduce the desired signal, and means for selectively detecting and utilizing only said frequency modulation so to control the characteristics of the receiver as to reduce the effects of said undesired signal disturbances.

3. A modulated-carrier signal receiver comprising means for selecting a carrier having frequency modulation representing a desired signal and subject to both frequency and amplitude modulation by undesired signal disturbances, means for selectively detecting and utilizing said frequency modulation to reproduce said desired signal, and means for selectively detecting and utilizing only said amplitude modulation so to control the characteristics of said receiver as to reduce the effects of said undesired signal disturbances.

4. A modulated-carrier signal receiver comprising means for selecting a carrier having a first characteristic type of modulation representing a desired signal and subject to modulation of said first type and of a second characteristic type by substantially continuous undesired signal disturbances, means including a band-pass selector for selectively detecting and utilizing said modulation of the first type to reproduce the desired signal, and means selectively responsive

only to modulation of said carrier of said second type for adjusting the width of the band of frequencies passed by said selector substantially to reduce the effect of said undesired signals.

5. A modulated-carrier signal receiver comprising means for selecting a carrier having a first characteristic type of modulation representing a desired signal and subject to modulation of said first type and of a second characteristic type by substantially continuous undesired signals on carriers adjacent the desired signal carrier, means including a band-pass selector for selectively detecting and utilizing said modulation of the first type to reproduce the desired signal, and means selectively responsive only to modulation of said carrier of said second type for adjusting the width of the band of frequencies passed by said selector substantially to reduce the effect of said undesired signals.

6. A modulated-carrier signal receiver comprising means for selecting a carrier having amplitude modulation representing a desired signal and subject to both amplitude and frequency modulation by substantially continuous signal disturbances, means including a band-pass selector for selecting, detecting, and utilizing said amplitude modulation to reproduce the desired signal, and means selectively responsive only to said frequency modulation of said carrier for adjusting the width of the band of frequencies passed by said selector in accordance with said undesired signal disturbances, thereby to reduce the effects thereof.

7. A modulated-carrier signal receiver comprising a main signal-translating channel including means for selecting a carrier having a first characteristic type of modulation representing a desired signal and subject to modulation of said first type and of a second characteristic type by undesired signal disturbances, means for selectively detecting and utilizing said selected-carrier modulation of the first type to reproduce the desired signal, adjustable means for reducing the effects of said undesired signal disturbances, an auxiliary signal-translating channel comprising means for selectively detecting only modulation of said carrier of said second type, and means for utilizing said selected-carrier modulation of said second type for controlling said adjustable means.

8. A modulated-carrier signal receiver comprising a main signal-translating channel including means for selecting a carrier having a first characteristic type of modulation representing a desired signal and subject to modulation of said first type and of a second characteristic type by substantially continuous undesired signal disturbances, an adjustable band-pass selector for translating said desired signal and means for detecting and utilizing said modulation of said first type to reproduce the desired signals, an auxiliary signal-translating channel coupled to said selecting means and including means for selectively detecting only modulation of said carrier of said second type, and means for utilizing said modulation of said second type for so adjusting the width of the band of frequencies passed by said selector as to reduce substantially the effects of said disturbances.

9. A modulated-carrier signal receiver comprising a main signal-translating channel including means for selecting a carrier having amplitude modulation representing a desired signal and subject to both amplitude modulation and frequency modulation by substantially continuous undesired

- signal disturbances, an adjustable band-pass selector for translating said desired signal, means for selectively detecting and utilizing said amplitude modulation to reproduce the desired signal, 5 an auxiliary signal-translating channel coupled to said selecting means and including means for selectively detecting only said frequency modulation, means for rectifying the detected frequency modulation to develop a control-bias voltage 10 variable in accordance with the amplitude of said undesired signal disturbances, and means for utilizing said bias voltage for adjusting the width of the band of frequencies passed by said selector substantially to reduce the effects of said disturbances. 15
10. A modulated-carrier signal receiver comprising a main signal-translating channel including means for selecting a carrier having a first characteristic type of modulation representing a 20 desired signal and subject to modulation of said first type and of a second characteristic type by substantially continuous undesired signals on the carrier adjacent the desired signal carrier, an adjustable band-pass selector for translating said 25 desired signal, means for detecting and utilizing said modulation of the first type to reproduce the desired signal, an auxiliary signal-translating channel coupled to said selecting means and including means responsive only to modulation of 30 the carrier of said second type for developing a control-bias voltage variable in accordance with said undesired carrier, and means for utilizing said bias voltage for adjusting the width of the band of frequencies passed by said selector substantially to reduce the effects thereof. 35
11. A modulated-carrier signal receiver comprising a main signal-translating channel including means for selecting a carrier having amplitude modulation representing a desired signal and subject to both amplitude and frequency 40 modulation by substantially continuous undesired signals on carriers adjacent the desired signal carrier, an adjustable band-pass selector for translating said desired signal, means for detecting and utilizing said amplitude modulation to reproduce the desired signal, an auxiliary signal-translating channel including means for selectively detecting only said frequency modulation to develop beat-note signals variable in accordance with the amplitude of said undesired signals, and means for utilizing said beat-note signals to adjust the width of the band of frequencies passed by said selector substantially to reduce the effect of said undesired signals. 55
12. A modulated-carrier signal receiver comprising means for selecting a carrier having a first characteristic type of modulation representing a desired signal and subject to modulation of said first type and of a second characteristic type by undesired signal disturbances of a discontinuous character, means for selectively detecting and utilizing said modulation of said first type to reproduce the desired signal, and means responsive only to said modulation of said carrier 60 of said second type for substantially suppressing the reproduction of both the desired signal and said undesired signal disturbances for the duration of said disturbances. 65
13. A modulated-carrier signal receiver comprising a main signal-translating channel including means for selecting a carrier having a first characteristic type of modulation representing a desired signal and subject to modulation of said first type and of a second characteristic type by 70 undesired signal disturbances of a discontinuous character and means including an amplifier for detecting, amplifying, and reproducing the desired signal, an auxiliary signal-translating channel coupled to said selecting means and including means for selectively detecting only modulation of said carrier of said second type, and means having negligible time delay for utilizing said modulation of said second type to reduce the conductance of said amplifier substantially to zero, thereby substantially to suppress the reproduction of both the undesired disturbances and said desired signal for the duration of said disturbances. 75
14. A modulated-carrier signal receiver comprising tunable means for selecting a carrier having a first characteristic type of modulation representing a desired signal and subject to modulation of said first type and of a second characteristic type by undesired signal disturbances caused by mistuning of said selecting means, 15 means for selectively detecting and utilizing said modulation of the first type to reproduce the desired signal, and means selectively responsive to modulation of the second type for substantially suppressing the reproduction of both the undesired signal disturbances and said desired signal when said selecting means is mistuned. 20
15. A modulated-carrier signal receiver comprising a main channel including tunable means for selecting a carrier having amplitude modulation representing a desired signal and subject to both amplitude and frequency modulation by discontinuous undesired signal disturbances caused by mistuning of said selecting means, 25 means including an amplifier for detecting, amplifying, and utilizing said amplitude modulation to reproduce the desired signal, a control channel coupled to said selecting means and including means for selectively detecting only said frequency modulation, and means having negligible time delay for utilizing said frequency modulation to reduce the conductance of said amplifier substantially to zero, thereby substantially to suppress the reproduction of both the undesired signal disturbances and said desired signal when said selecting means is mistuned. 30
16. A modulated-carrier signal receiver comprising means for selecting a carrier having a first characteristic type of modulation representing a desired signal and subject to modulation of said first type and of a second characteristic type by electrical transients, means for selectively detecting and utilizing said modulation of said first type to reproduce the desired signal thereby incidentally reproducing said transients, and means 35 selectively responsive only to modulation of said carrier of said second type substantially to suppress the reproduction of both the transients and said desired signal for the duration of said transients. 40
17. A modulated-carrier signal receiver comprising a main channel including means for selecting a carrier having amplitude modulation representing a desired signal and subject to both amplitude and frequency modulation by electrical 45 transients, means including an amplifier for amplifying, detecting, and utilizing said amplitude modulation to reproduce the desired signal thereby incidentally reproducing said transients, a control channel coupled to said selecting means and including means for selectively detecting only said frequency modulation, and means having negligible time delay for utilizing said frequency modulation to reduce the conductance of said amplifier substantially to zero, thereby substan- 50

tially to suppress the reproduction of both said transients and said desired signal for the duration of said transients.

18. A modulated-carrier signal receiver comprising means for selecting a carrier having a first characteristic type of modulation representing a desired signal and subject to modulation of said first type and of a second type by substantially continuous undesired signal disturbances and by 10 undesired signal disturbances of a discontinuous character, means including a band-pass selector and an amplifier for selecting, detecting, amplifying, and utilizing said modulation of said first type to reproduce the desired signal, means se-

lectively responsive only to modulation of said carrier of the second type by continuous undesired signals for adjusting the width of the band of frequencies passed by said selector substantially to reduce the effects of said continuous disturbances, and means responsive only to modulation of said carrier of said second type by said disturbances of a discontinuous character for controlling said amplifier substantially to suppress the reproduction of all desired and undesired signals for the duration of discontinuous signal disturbances. 5 10
